His ATTORNEYS.

UNITED STATES PATENT OFFICE

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA

CAR ROOF

Application filed December 31, 1930. Serial No. 505,759.

This invention relates to car roofs of the all-steel riveted-up type wherein the roof sheets are supported at the eaves of the car on inwardly extending portions of the side plates and are rigidly secured to each other by weatherproofing seam caps that function as outside carlines; and more particularly it relates to the sub-type of roof wherein the seam caps have base flanges that rest upon the raised panels formed in the adjacent margins of the roof sheets. The principal object of the present invention is to provide simple and efficient weatherproof means independent of the side plates for holding in contact with each other the portions of the base flanges of the seam caps and the roof sheet that are located above the inwardly extending sheet supporting portions of said side plates. Another object is to provide means for transmitting the load from the seam caps to the roof sheet supporting portions of the side plates without crushing the raised side marginal panels of the roof sheets. Other objects are cheapness of construction, compactness of design and fewness of parts. The invention consists principally in the combinations and arrangements of parts hereinafter described and claimed.

In the accompanying drawings, which form part of this specification and wherein like symbols refer to like parts wherever they occur,

Fig. 1 is a plan view of a portion of an all-steel riveted-up car roof embodying my invention,

Fig. 2 is an enlarged vertical transverse section through one half of the roof between seam caps on the line 2-2 in Fig. 1,

Fig. 3 is a vertical longitudinal cross-section taken longitudinally of the roof sheet supporting flange of a side plate at one of the seam caps on the line 3-3 in Fig. 1,

Fig. 4 is a vertical transverse section through the eaves portion of the roof, the section being taken through one of the raised side marginal panels of a roof sheet on the line 4-4 in Fig. 3,

Fig. 5 is a cross-sectional view similar to Fig. 3, showing a modified form of filler plate; and

Fig. 6 is a vertical cross-section on the line 6-6 in Fig. 5.

Referring to the accompanying drawings, my invention is shown in connection with a car roof having side plates A substantially Z-shaped in cross-section with the inner leg 1 upstanding and provided at its top with an inwardly extending flange 2 disposed at an angle conforming to the pitch of the roof and at the proper elevation for the end portions of metal roof sheets 3 to rest upon. As shown in the drawings, the inwardly extending roof sheet supporting flange 2 is formed integral with the side plate; but, in some instances, it may be desirable to make such flange in the form of a separate member and rivet it to the side plate.

The roof sheets 3 slope downwardly from the ridge to the side plates A where they are provided with depending eaves flanges 4 that overhang the upstanding inner legs 1 of said side plates and are rigidly secured to the outer faces of said legs by rows of horizontal rivets 5. The body portion of the roof sheets 3 are offset upwardly to form raised side marginal panels 6 which merge into said body portions where they are turned down to form the depending eaves flanges 4. The roof sheets are provided at their side edges with upstanding seam flanges 7 that extend from end to end of the sheets and are bent down with the end portion of the sheets that form the eaves flanges 4. The side seam flanges 7 are of substantially uniform depth from ridge to the points adjacent to the eaves where their depth is decreased to permit the eaves end portions to be turned down without rupturing the metal or galvanizing.

The adjacent upstanding side seam flanges 7 of the roof sheets are covered by weatherproofing members preferably in the form of inverted U-shaped combined seam caps and outside carlines 8, which extend from eaves to eaves of the car and are rigidly secured to said sheet flanges by rows of rivets 9. The hollow ribs of the seam caps 8 decrease in depth uniformly from ridge to points adjacent to the eaves where they slope downwardly and are turned down over the down-turned ends of the side seam flanges 7 of the

5 roof sheets. The seam caps 8 are provided at the lower edges of the side walls of their hollow ribs with outstanding base flanges 10 that bear flatwise upon the side marginal panels 6 of the adjacent roof sheets and are turned down over the depending eaves flanges 4 of said sheets and secured to the side plates by the rivets 5. As the depth of the hollow ribs of the seam caps 8 decrease 10 from the ridge towards the eaves, there is a corresponding increase in the width of the base flanges 10 from the ridge towards the eaves.

15 Located between the raised side marginal panels 6 of adjacent roof sheets and the inwardly extending roof sheet supporting flanges 2 of the side plates are filler members or plates 11. The filler members 11 extend longitudinally of the roof sheet supporting flanges 2 from the inner edge of one roof sheet panel to the inner edge of the adjacent roof sheet panel and are preferably of a thickness corresponding to the space between said panels and said roof sheet supporting flanges. The filler plates 11 are rigidly secured to the undersides of adjacent side marginal roof sheet panels 6 by means of rivets 12 that pass through the base flanges 10 of the seam caps 8 and thus 20 serve to hold the eaves portions of said base flanges in contact with upper surfaces of said side marginal sheet panels. As shown in the drawings, the rivets 12 which tightly clamp the raised marginal sheet panels 6 between the filler plates 11 and the base flanges 10 of the seam caps 8, have their lower heads countersunk in the bottom of said filler plates so as to enable said filler plates to bear 25 flatwise upon the inwardly extending sheet supporting flanges 2 of the side plates.

30 In the modified construction shown in Figs. 5 and 6, the eaves filler plate is shown in the form of a pressed metal member 11a having downwardly extending cross ribs 11b pressed therein intermediate its ends that bear upon the sheet supporting flange 2 of the side plate. With this arrangement, the major portion of the strip 11a bears flatwise 35 against the undersides of the raised side marginal sheet panels 6, and the end portions of said strip are spaced far enough above the sheet supporting flange 2 of the side plate to accommodate the flat heads at the lower ends of the securing rivets 12a, thereby 40 eliminating the necessity for countersinking the lower heads of the rivets in the filler member.

45 By the arrangement described, the base flanges 10 of the seam caps 8 are firmly held in contact with the raised side marginal panels 6 of the roof sheets where the height of the upstanding seam flanges 7 is reduced, thereby 50 preventing water from getting under the seam cap flanges at this point and being forced over the shallow eaves portions

55 of said flanges and thus entering the car. The rivets 12, which secure the seam cap flanges 10 to the raised side marginal panels 6 of the roof sheets, are located above the inwardly extending sheet supporting flanges 70 of the side plates 2, but they do not extend through said flanges, with the result that any water that leaks through the holes for 60 said rivets will be deposited upon said roof sheet supporting flanges and flow therefrom to the outside of the car. The filler plates 11 are supported on the sheet supporting flanges 2 and thus serve to transfer the roof load from the seam caps 8 to the side plates A without crushing the roof sheet panels 6. 80 The lower ends of the rivets 12 are flush with the underside filler plates 11 and thus permit said plates to bear flatwise upon the roof sheet supporting flanges 2 of the side plates. In assembling the roof, the filler plates 11 are preferably riveted in place before the roof is applied to the car, after which the complete roof is lifted with a crane and attached to the car by riveting the downturned eaves ends of the roof sheets and seam caps 90 to the upstanding inner legs 1 of the side plates.

95 What I claim is:

1. A car roof comprising side plates, roof sheets supported on said side plates, said roof sheets being provided along their adjacent margins with upstanding seam flanges, seam caps covering the upstanding seam flanges of adjacent roof sheets and having lateral base flanges that overlie the body portions thereof, and means for rigidly securing the base flanges of said seam caps to the body portions of said roof sheets, said means being independent of the means for securing said sheets and caps to the substructure that supports them. 100

105 2. A car roof comprising side plates, roof sheets supported on said side plates, said roof sheets being provided along their adjacent margins with upstanding seam flanges, seam caps connecting the upstanding seam flanges of adjacent roof sheets and having lateral base flanges resting on the body portions thereof, and means for rigidly securing the eaves end portions of the base flanges of said 110 seam caps to the body portions of said roof sheets, said means being independent of the means for securing said sheets and caps to the substructure that supports them. 115

120 3. A car roof comprising side plates, roof sheets extending from side plate to side plate and rigidly secured thereto, said roof sheets being provided along their adjacent margins with upstanding seam flanges, seam caps straddling the upstanding seam flanges of adjacent roof sheets and having lateral base flanges resting on the body portions thereof, and means for rigidly securing the base flanges of said seam caps to the body portions 125 of said roof sheets, said means being inde- 130

- pendent of the means for securing said sheets and caps to the substructure that supports them.
4. A car roof comprising side plates, roof sheets supported on said side plates, said roof sheets being provided along their adjacent margins with upstanding seam flanges, seam caps covering the seam flanges of adjacent roof sheets, said seam caps having outstanding base flanges that bear flatwise upon the body portions of adjacent roof sheets, a plurality of members disposed beneath adjacent roof sheets, and means for rigidly securing said members to the undersides of said roof sheets and for rigidly securing to the upper-sides of said roof sheets the base flanges of said seam caps, said means being independent of the means for securing said sheets and caps to the substructure that supports them.
5. A car roof comprising side plates, roof sheets extending from side plate to side plate and rigidly secured thereto, said roof sheets being provided along their adjacent margins with upstanding seam flanges, seam caps covering said seam flanges and rigidly secured thereto and provided with outstanding base flanges, a plurality of members extending beneath adjacent roof sheets, and means for rigidly securing said members to the base flanges of said seam caps with the bodies of the sheets clamped therebetween, said means being independent of the means for securing said sheets and caps to the substructure that supports them.
6. A car roof comprising side plates, roof sheets extending from side plate to side plate and rigidly secured thereto, said roof sheets being provided along their adjacent margins with upstanding seam flanges, seam caps covering said seam flanges and rigidly secured thereto, said seam caps having outstanding base flanges that overlie the body portions of adjacent roof sheets, a plurality of members disposed cross-wise of said seam caps beneath adjacent roof sheets, and means for rigidly securing the end portions of said members and the base flanges of said seam caps to the bodies of the roof sheets, said means being independent of the means for securing said sheets and caps to the substructure that supports them.
7. A car roof comprising side plates having inwardly extending roof sheet supports, roof sheets supported on said roof sheet supports and provided with upstanding flanges at their side edges, seam caps covering the side flanges of adjacent roof sheets, said seam caps having outstanding base flanges overlying the body portions of adjacent sheets, and means located above and independent of the roof sheet supports for rigidly securing said base flanges of said seam caps to the bodies of said roof sheets.
8. A car roof comprising side plates having inwardly extending roof sheet supports, roof sheets supported on said roof sheet supports and provided with upstanding flanges at their side edges, seam caps covering the side flanges of adjacent roof sheets, said seam caps having outstanding base flanges overlying the body portions of adjacent sheets, and means located above and independent of the roof sheet supports for rigidly securing said base flanges of said seam caps to the bodies of said roof sheets.
9. A car roof comprising Z-shaped side plates with their webs horizontal and the inner legs extending upwardly and having inwardly extending roof sheet supporting flanges at the top thereof, roof sheets supported on said inwardly extending roof sheet supporting flanges with their ends turned down and rigidly secured to the inner legs of said side plates, said roof sheets being provided along their adjacent margins with upstanding seam flanges, seam caps covering said flanges and rigidly secured thereto, said seam caps having outstanding base flanges overlying the body portions of adjacent roof sheets, and means located above and independent of said roof sheet supporting flanges for rigidly securing the base flanges of said seam caps to the bodies of said roof sheets.
10. A car roof comprising Z-shaped side plates with their webs horizontal and the inner legs extending upwardly and having inwardly extending roof sheet supporting flanges at the top thereof, roof sheets supported on said inwardly extending roof sheet supporting flanges with their ends turned down and rigidly secured to the inner legs of said side plates, said roof sheets being provided along their adjacent margins with upstanding seam flanges, seam caps covering said flanges and rigidly secured thereto, said seam caps having outstanding base flanges overlying the body portions of adjacent roof sheets, means located above and independent of said roof sheet supporting flanges for rigidly securing the base flanges of said seam caps to the bodies of said roof sheets, said means comprising members disposed between said roof sheets and said sheet supporting flanges, and rivets that are located entirely above said roof sheet supporting flanges and extend through the base flanges of said seam caps, the bodies of said roof sheets and the members located therebelow.
11. A car roof comprising Z-shaped side plates with their webs horizontal and the inner legs extending upwardly and having inwardly extending roof sheet supporting flanges at the top thereof, roof sheets supported on said inwardly extending roof sheet supporting flanges with their ends turned down and rigidly secured to the inner legs of

- said side plates, said roof sheets being provided along their adjacent margins with upstanding seam flanges, seam caps covering said flanges and rigidly secured thereto, said seam caps having outstanding base flanges overlying the body portions of adjacent roof sheets, means located above and independent of said roof sheet supporting flanges for rigidly securing the base flanges of said seam caps to the bodies of said roof sheets, said means comprising members disposed between said roof sheets and said sheet supporting flanges, and rivets that are located entirely above said roof sheet supporting flanges and extend through the base flanges of said seam caps, the bodies of said roof sheets and the members located therebelow, said rivets terminating at their lower ends flush with the undersurfaces of said members.
- 10 12. A car roof comprising side plates, roof sheets supported on said side plates, said roof sheets being provided along their adjacent margins with upstanding seam flanges, seam caps covering the upstanding seam flanges of adjacent roof sheets and having lateral base flanges that overlie the body portions thereof, and means for rigidly securing the base flanges of said seam caps to the body portions of said roof sheets, said means comprising plates extending beneath the adjacent roof sheets, and rivets passing through said plates, said roof sheets and the base flanges of said seam caps only.
- 15 13. A car roof comprising side plates with inwardly extending sheet supporting flanges, roof sheets extending from side plate to side plate with their end portions supported on the inwardly extending sheet supporting flanges thereof and having depending eaves flanges rigidly secured to the vertical faces of said side plates, said roof sheets being provided along their adjacent margins with raised panels having upstanding flanges at their edges, seam covers straddling the upstanding flanges of adjacent sheets and having laterally extending base flanges resting on the raised panels thereof, filler plates located beneath the raised panels of adjacent roof sheets above the inwardly extending flanges of the side plates, and means located above and independent of said sheet supporting flanges for rigidly securing together the base flanges of said seam caps, the side marginal panels of said roof sheets and said members.
- 20 14. A car roof comprising side plates with inwardly extending sheet supporting flanges, roof sheets extending from side plate to side plate with their end portions supported on the inwardly extending sheet supporting flanges thereof and having depending eaves flanges rigidly secured to the vertical faces of said side plates, said roof sheets being provided along their adjacent margins with raised panels having upstanding flanges at their edges, seam covers straddling the upstanding flanges of adjacent sheets and having laterally extending base flanges resting on the raised panels thereof, filler plates located beneath the raised panels of adjacent roof sheets above the inwardly extending flanges of the side plates, means independent of said sheet supporting flanges for rigidly securing together said members and the base flanges of the seam caps with the side marginal panels of the roof sheets therebetween, each of said filler members comprising a sheet of metal having portions that bear upon and portions that are spaced above the inwardly extending sheet supporting flanges of said side plates, and rivets passing only through the base flanges of said seam caps, the raised panels of said roof sheets and the portions of said filler members that are spaced above said side plates, said rivets having headed lower end portions disposed between said flanges and said last mentioned portions of said filler members.
- 25 15. A car roof comprising side plates with inwardly extending sheet supports, roof sheets extending from side plate to side plate with their end portions supported on said supports, said roof sheets being provided along their adjacent margins with raised panels having upstanding seam flanges at their edges, seam covers connecting the upstanding flanges of adjacent roof sheets and having laterally extending base flanges overlying the raised panels thereof, and means located above and independent of said roof sheet supports for rigidly securing the base flanges of said seam caps to the side marginal panels of said sheets.
- 30 Signed at New Kensington, Pennsylvania, this 26th day of December, 1930.
- CHARLES DAVID BONSALL.
